Patented Nov. 6, 1973

229,061

COMBINED PEGBOARD AND BLACKBOARD

Lynn Pressman, 200 5th Ave., New York, N.Y. 10010

Filed Dec. 17, 1971, Ser. No. 209,488

Term of patent 14 years

Int. Cl. D19—07

U.S. Cl. D25—1 R

FIG. 1

FIG. 2

FIG. 3

FIG. 4

FIG. 1 is a right side front perspective view of a combined pegboard and blackboard embodying my new design, it being understood that the pegholes always cover the entire surface in uniform rows;

FIG. 2 is a left side elevational view thereof;

FIG. 3 is a top plan view thereof, the bottom plan being identical; and

FIG. 4 is a right side top rear perspective view thereof.

I claim:

The ornamental design for a combined pegboard and blackboard, as shown and described.
